UNITED STATES PATENT OFFICE

2,511,139

ELECTRIC AIR CIRCULATING HEATER

Charles K. Yeamans, Houston, Tex.

Application February 11, 1947, Serial No. 727,907

2 Claims. (Cl. 219—39)

1

This invention relates generally to heating and ventilating apparatus and is directed particularly to novel means for warming and cooling particular bodies, especially mattresses.

A principal object of the present invention is to provide a novel apparatus whereby the mattress of a bed may be ventilated and cooled in the summer time or may be warmed in the winter by introducing warm air into the body of the mattress or by drawing air out from within the same as desired.

A further and more specific object of the invention is to provide a novel air heating and circulating unit which is adapted to be coupled with an air vent opening in the side wall of a mattress and which may be stood under or adjacent to the bed upon which the mattress is placed and operated to warm the mattress by blowing heated air thereinto or to cool the mattress by sucking the air out of the same.

The invention will be best understood from a consideration of the following detailed description taken in connection with the accompanying drawing forming a part of the specification, with the understanding, however, that the invention is not confined to a strict conformity with the showing of the drawing but may be changed or modified so long as such changes or modifications mark no material departure from the salient features of the invention as expressed in the appended claims.

In the drawing:

Figure 1 is a view partly in vertical section and partly in side elevation of an apparatus constructed in accordance with the present invention whereby the introduction of warm air into or the extraction of air from a mattress may be accomplished.

Figure 2 is a view in top plan of the unit with the air conductor tube removed therefrom.

Figure 3 is a horizontal section taken substantially on the line 3—3 of Figure 1.

Figure 4 is a view in elevation of a portion of a mattress body showing the usual screened vent openings with one of which the air heater and circulator shown in Figure 1 is connected.

Referring now more particularly to the drawing there is shown in Figure 1 the air circulating and heating apparatus forming a part of the present invention. This unit as shown is in the form of a hood or housing, here shown as being of circular cross section and generally designated 10. This housing has an open underside or bottom portion 11 and the side wall 12 of the housing merges into a horizontal top wall 13 which is continued upwardly at the vertical center of the

2

housing to form the outlet nozzle and coupling 14.

The open underside of the housing is maintained a slight distance above the floor or other surface by the supporting legs 15 whereby air may be drawn upwardly into the housing or discharged downwardly therefrom as desired.

Within the housing 10 adjacent to the open lower part thereof, is mounted an air heating unit which is generally designated 16. This heating unit may be of any suitable character and may be mounted in any desired manner. The structure here shown comprises a ring 17 of insulation material within which is supported an electrical incandescent heater which comprises a plurality of resistant coils 18 connected in series in the usual manner of heating devices of this kind. This unit is supported by providing a number of inwardly directed lugs 19 upon the inner surface of the wall 12, to which the insulation ring 17 is secured by suitable attaching units such as bolts 20 or the like.

Within the housing above the heating unit 16 is supported an electric motor with the shaft coaxial with the nozzle 14. The downwardly directed end of the motor armature shaft, not shown, carries a fan unit which is generally designated 22 and which when operated in one direction draws air in through the open lower end 11 of the housing through the heater, for discharge through the nozzle 14 and when operated in the opposite direction it draws the air in through the nozzle 14 and discharges it downwardly through the open bottom of the housing. Accordingly it will be understood that this motor is of the reversible, variable speed type.

While the motor 21 may be mounted in any suitable manner, it is here shown as supported by a series of lugs 23 secured at the inner end of the nozzle 14 and bolted to the motor housing by the securing elements or bolts 24.

Adapted for connection at one end with the nozzle 14 of the housing 10, is an air tube or hose 25, the other end of which is designed to be connected with an opening in one side wall of the mattress which is to be heated or cooled by the present device.

The numeral 26 generally designates a portion of a conventionally illustrated mattress, looking at the side wall thereof. As is well known mattresses of the inner spring type are equipped in the side walls with ventilating openings which are usually covered by a screen so that as the mattress is used, the movements of the occupant thereof will cause air to move into and out of the mattress through such ventilating openings.

In accordance with the present invention the

openings 27 in the side walls of the mattress have secured thereover the apertured inner and outer plates 28 and 29 respectively, the outer plate carrying the tubular coupling or nozzle 30 with which the other end of the air conducting pipe or tube 25 is connected.

A suitable screen in the form of a wire fabric is interposed between the apertured plates 28 and 29 to cover the opening in the mattress wall, such screen being designated 31.

In the use of the present invention if it should be desired to cool and ventilate the mattress the unit 10 is connected with one of the vent openings in a wall of the mattress and the fan 22 is operated by the motor 21 in a direction to draw the air from within the mattress and discharge it through the open underside 11 of the housing. As will be readily apparent in operating the unit in this fashion air will be drawn in through one of the screened vent openings and then extracted 20 through the opening to which the tube 25 is attached.

If it should be desired to warm the inside or interior of the mattress then the direction of rotation of the fan 22 is reversed by the electric motor 21 and electric current is run from a suitable source through the resistant units 18 to heat the latter to incandescence. The air is then drawn in through the bottom of the housing and forced through the tube 25 into the mattress through which it will flow to one of the screened ports through which it escapes.

From the foregoing it will be readily apparent that there is provided in the present invention a simple but efficient means for heating or cooling a mattress structure whereby its use in winter or summer may be made more comfortable.

I claim:

1. An air conditioner and circulator of the character and for the purpose set forth, comprising a vertical housing having an open lower end, a nozzle leading from a central opening in the top wall of said housing, an electric motor supported

within the housing and having an armature shaft coaxial with the nozzle, one end of the motor being disposed within the lower end of the nozzle, lugs spaced about the nozzle opening in the top wall of said housing, bolts for removably securing said motor to said lugs, a fan carried upon said shaft, supporting legs for the housing maintaining the open lower end raised from a supporting surface, an annulus removably supported within the lower end of the housing, a heating unit supported within said annulus, and a duct leading from said nozzle for conveying the heated air to a place of need.

2. An air conditioner and circulator of the character stated in claim 1 wherein the said annulus is supported from the underside of a plurality of other lugs secured in spaced relation about the side wall of and within the housing and is removably secured thereto by bolts.

CHARLES K. YEAMANS.
